UNITED STATES PATENT OFFICE.

RICHARD T. BURKE, OF NEW ORLEANS, LOUISIANA.

DEVICE FOR AUTOMATICALLY PRINTING DATA ON RACING PROGRAMS.

Application filed March 20, 1926. Serial No. 96,258.

This invention relates to improvements in devices for automatically printing data on racing programs or the like.

The prime object of this invention is to 5 provide means for automatically printing the jockeys' names on the racing programs.

A further object of this invention is to 10 provide time saving means and a convenient method for noting the names of jockeys on racing programs, thereby obviating the old and common method of writing the names of the jockeys in long hand.

It is to be understood that the names of 15 the jockeys on these racing programs are exceedingly essential and are not authentically available at the time the racing programs are issued for sale, usually in the early part of the day.

A further object of this invention is to 20 provide an automatic means for printing the names of the jockeys on the racing program by the simple procedure of inserting a coin in a slot, thereby causing the device to function and deliver the racing program with 25 the names of the jockeys properly located thereon and insuring accurate information as to the jockeys and their respective mounts in relation to the program.

Even in the countries where the information 30 concerning the jockeys is printed on the racing program, it is subject to change before post time, and therefor this invention provides an efficient means of speedily and 35 conveniently supplying the names of the jockeys on the racing programs.

Further objects will appear in the following detailed description of this invention and in the several sheets of drawings which are herewith made a part of this application. 40

In the drawings,

Fig. 1 illustrates a front elevational view of the automatic printing machine.

Fig. 2 represents a rear elevational view of 45 the automatic printing machine.

Fig. 3 is a top plan view of the machine.

Fig. 4 illustrates an end elevational view of the automatic printing machine.

Fig. 5 represents an end elevational view 50 of the machine.

Fig. 6 illustrates a sectional elevational view taken along line 6—6 of Fig. 1.

Fig. 7 represents an end elevational view 55 of the driving motor and shaft with the magnetic breaker mechanism in assembled relationship thereto.

Fig. 8 is a front elevational view of a portion of the slot mechanism, showing a coin in position whereby the circuit is closed and the machine is put in operation. 60

Fig. 9 represents a vertical sectional view taken along line 9—9 of Fig. 9.

Fig. 10 illustrates a cross sectional view of the type carrying drum disclosing the clamping means for firmly holding the type carrying receptacle in place on the drum. 65

Fig. 11 is a view of a portion of the type carrying device showing connected thereto end elements consisting of a knurled surface for firmly gripping the program when passing through the machine and a reading scale designating the posts of horses and jockeys. 70

Fig. 12 is a perspective view of the receptacle for the type.

Fig. 13 is a diagrammatic view of a portion of a program commonly distributed at race tracks, showing the post and horse, the name of the jockey being provided by this invention. 75

Numeral 1 designates a frame adapted for carrying the device for automatically printing jockeys' names on racing programs, the device consisting of drums 2 and 3, the drums having suitable receptacles 4, for holding or carrying the type 5, designating the names of jockeys or otherwise. The type 5 may be comprised of any suitable material such as rubber or otherwise and adapted to be held in a removable receptacle 6, each name having a separate receptacle 6. These receptacles containing the typed names are positioned in each of the cylinder type carrying drums 2 and 3. 80

Suitably positioned above the type carrying drums 2 and 3 are located inking rolls 7 and 8 which are rotatably carried in the frame work 1, the ink pads 9 being located along the rolls 7 and 8 and properly spaced thereon so as to cooperate with the type on the typing rolls, the ink pads being adjusted to lightly contact with the revolving face of the type. 85

Suitably positioned at the upper portion of the frame work 1 is a chute or guide portion 10 adapted to receive the racing program 11 which is to be supplied with additional data preferably the names of jockeys which are set in type on the revolving drums 2 and 3. The program 11 being inserted in the guide portion 10, is adapted to rest upon the type carrying drum 3, that is, the top or upper drum. Cooperating with the two type 100

105

110

carrying drums and the two inking rolls are 5 guide rolls 12 and 13, adapted to guide the program through the device. When in operation the type carrying drums together with the various other rotating elements are 10 adapted to be driven from any suitable source of power, preferably a small electric motor having a driving shaft 14, adapted to drive a series of reduction gearings 15, 16, 17, 18, 19, 20, and 21, connecting the type carrying drums and other moving parts.

The driving motor 22 is adapted to be 15 suitably located and held in place in the frame 1 having mounted on its driving shaft 14 a brake wheel 24. Suspended from the frame 1 is a bracket portion 25, adapted to carry the brake and band 27, and magnet coil 34 in such a manner that when the electric current is turned on by inserting a coin 20 in slot 29, the magnet 25 releases a counter-balance weight 26, and permits the device to operate. When the current is turned off, the magnet 25 releases its hold and the counter-balance weight 26 clamps a friction band 27 25 around the driving shaft 14, and causes the motor to stop in its proper place for the next operation.

Suitably attached to the frame work 1 is 30 a register 27' for counting the number of programs printed by this device. This register may be operated in the usual manner by means of a contact lug on one of the type carrying drums 2. At each end of the type carrying drums 2 and 3 is positioned a scale 35 33, designating the post position of the horse. In order to operate this device, a coin 35 preferably a dime is inserted in a slot 29 and functions to close the circuit at points 36 and 37, thereby starting the motor 22. On 40 revolving one revolution, the coin is forced out by contact means of the pin member 30, suitably located on revolving drum 3, thereby opening the circuit and completes the operation. The pin 30 is mounted on the shaft 45 of the type carrying cylinder member 3, and is made of a nonconductive material, preferably fibre.

The frame work 1 suitably supports an 50 apron portion 31 upon which the program is adapted to be delivered.

In operation this invention provides a device for automatically printing data on a racing program, such as for instance, the names of jockeys. The racing program may 55 be merely inserted in the slot or guide por-

tion, and a coin or slug placed in the coin slot thereby completing the circuit and causing the device to operate, the program being carried through the machine and printed on both sides simultaneously. The program is 60 aided in its travel through the device by means of knurled surfaces located at suitable points on the type carrying drums 2 and 3, preferably near the ends thereof, the program being then delivered from the machine upon an apron or other suitable delivery point.

This invention provides an efficient means for supplying patrons at race tracks or other similar places with authentic and valuable 70 information, automatically operated by a suitable source of power such as an electric motor, and through a coin or slug control, the device printing simultaneously on both sides of the sheet or program, the insertion 75 of the coin or slug causing the magnetic brake to function.

This invention relieves a patron of a race track from all inconvenience of using a pencil in noting this information from the ordinary blackboard in common use. The complete operation of obtaining the information by means of this invention requires but a few seconds as can be readily understood and the information is accurate. 85

It is to be understood that the invention as herewith described and claimed covers but one modification, obviously, various changes, variations, substitutions and numerous modifications may be resorted to without departing from the spirit and scope of this invention. 90

What I claim is:

A coin controlled slot machine for automatically printing the names of jockeys on 95 both sides of a racing program in the same operation, rotatable cylindrical sections for carrying the printing type inking rolls, guiding elements adapted to guide the program through the machine during the process of printing, knurled surfaces on the cylindrical sections, a scale on the cylindrical sections to be read in connection with the name of the jockey being printed, thereby clearly showing the post of the horse on the program, which the jockey is to ride. 100

In testimony whereof I affix my signature. 105

RICHARD T. BURKE.
